(57) **CLAIM**

The ornamental design for an earbuds with charging case, as
shown and described.

DESCRIPTION

FIG.1 is a front perspective view of an earbuds with charg-
ing case showing the new design in an opened state;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the earbuds of the
earbuds with charging case, shown separately to show
aspects of the design that are not visible when combined;

FIG. 10 is a second perspective view thereof;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof;

FIG. 17 is a front perspective view of the charging case of
the earbuds with charging case, shown separately to show
aspects of the design that are not visible when combined;
and,

FIG. 18 is a back perspective view thereof.

The broken lines shown in the drawings depict portions of
the earbuds with charging case that form no part of the
claimed design.
